7 Claims. (Cl. 250—158)

This invention relates to improvements in electrostatic deflector systems of cathode-ray oscilloscopes and television tubes. Its object is to provide a new deflector system, with high deflection sensitivity, which is suitable for much wider deflection angles than hitherto used, and allows constructing very short cathode-ray tubes with large screens.

One feature of the invention comprises an improved deflector system which includes two sets of successively arranged deflecting electrodes, such electrodes being so energized as to produce opposite oscillatory deflections of the electron stream. A further feature of the invention consists in arranging the various sets of deflecting electrodes in the configuration of split cylinders and by this means producing deflections in two planes at a common pivot point. According to a further feature of the invention, the deflecting system is followed by an electrostatic lens having its first nodal point coincident with the pivot point of the deflecting system, or as near to such point as possible. According to a still further feature of the invention, in order to eliminate the astigmatism of the deflecting rays, the deflecting system is so arranged as to produce a cross-over of the rays of the electron beam at a point within the deflecting structure. As a further aspect of this feature, an electrostatic lens follows the deflecting system in such location that the lens focuses an image of the said cross-over on the fluorescent screen. The pivot point of the beam is caused to coincide as nearly as possible with the nodal point of the lens.

In the drawings, Fig. 1 is a sketch of the new deflecting system in the simplest case; Figs. 2 and 3 are drawings of a deflecting system which produces deflections in two perpendicular directions; Fig. 4 illustrates a complete electron gun fitted with such a deflector system; Fig. 5 is a deflector system with a lens behind it; Fig. 6 is a diagram showing the cardinal points of said lens and the refraction of electron rays in it; Figs. 7 to 9 are drawings of modified deflector systems; Fig. 10 is a sketch showing the astigmatism resulting from electrostatic deflection; Fig. 11 shows the principle by which this is eliminated in accordance with the present invention; Fig. 12 is an example of an anastigmatic gun and deflector system according to the invention; Fig. 13 is a diagram explaining the refraction of electron rays in Fig. 12; Fig. 14 is an improved design of an electron gun according to the invention; Fig. 15 is a drawing of a complete cathode-ray oscilloscope or television tube fitted with the

new gun and deflector system, and Fig. 16 is a diagrammatic representation showing the manner of connection and energization of the deflecting electrodes.

In Fig. 1, which is a longitudinal section of a particularly simple design of a deflector system according to the invention, 1, 2, 3 and 4 are deflector plates, which are connected crosswise, i. e., 1 is connected with 4 and 2 with 3. The two systems 1—2 and 3—4 will therefore deflect the electrons in opposite directions. Systems of crosswise connected deflector plates have been already used in cathode-ray oscilloscopes in so-called "beam traps," i. e., in designs in which it was intended to cut off the undeflected beam, or, in some systems, to cut off the deflected beam. It was not known, however, that such systems if suitably dimensioned can have deflecting sensitivities superior to simple deflecting condensers. This seems surprising, as the two systems are acting against each other. The explanation is contained in Fig. 1, which shows the case of optimum dimensions, in which the length of the first deflector system x_1 is $\frac{1}{3}$ of the length x_2 of the second system, i. e., $\frac{1}{4}$ of the total length. In this case $\frac{1}{3}$ of the length of the second system is used for compensating the deflection angle produced by the first system. In the remaining $\frac{2}{3}$ a stronger deflection in the opposite direction is produced. The deflected beams describe approximately parabolic paths. It follows therefrom that the deflected beam will pivot around a point P at a distance from the hind edge of the plates, equal to $\frac{1}{8}$ of the total length of the system. Thereby very large deflecting angles are produced. At the maximum deflecting voltage at which the beam can still pass through the plates it just grazes the plate 3 and the edge of 4. We see, therefore, that the spacing of the plates is fully utilized in this system, whereas it is only half utilized in simple deflecting condensers. Calling E the driving voltage of the electrons, V the maximum deflecting voltage and α the maximum deflecting angle, the following relation holds for simple condensers: $V/E = 2\tan^2\alpha$ whereas for the system shown in Fig. 1 this becomes $V/E = \tan^2\alpha$. The deflection sensitivity obtainable for a given maximum deflecting angle is therefore doubled in the new system.

The described case, in which x_2/x_1 is 3, gives maximum sensitivity. If x_2 is chosen larger, the deflected beam will be cut off by the edge of 4, if x_2 is chosen smaller, an advantage will be retained as compared with the simple system so

long as the edge of the second system is behind the point Q, at which in the optimum system the deflected beam cuts the axis. In this case $x_2/x_1=2.414$, and the pivot point coincides with the ends of the deflector system. In these approximate calculations the edge field has not been taken into account. In reality the optimum ratio x_2/x_1 is smaller than 3, as the edge fields add to the deflection produced by the second system, but detract from the deflections produced by the first.

The new system offers particular advantages, if each of the successively arranged two deflecting systems is shaped as a split tube. This is shown in Figs. 2 and 3 which are side and end views respectively of such a system. The cylinder segments 5 through 8 form the first, and 9, 10 and 11 with its opposite segment, not shown in the drawings, form the second system. 6 is connected with 9, 5 and 10, etc. If the condenser systems 5-6 and 7-8 are connected with potentials symmetrical to the same potential level, the field between them is approximately homogeneous over a great part of the cross section. This system will therefore produce deflections in both directions and occupy only the space of a single deflector system.

Fig. 4 shows a complete electron gun and deflector system of the last described kind. In Fig. 4, 12 is the cathode, 13 the modulating grid, 14 the first anode, 15 the second anode, 17 the first and 18 the second deflector system. The mean potential of the deflector systems is equal to the final driving voltage of the tube. Therefore between 15 and 17, an electron lens is formed, which projects the image of the cathode, or of the "cross-over" formed near the opening of 16 on the screen. It is seen that in spite of the slender shape of this system, very wide deflecting angles are obtained. According to the approximate calculation with parabolas the maximum angle in this case is 36°, in reality it can be even larger—45°—as the edge field of 18 increases the deflection after the electrons have left the system.

According to a further feature of the invention, the deflecting sensitivity of this system can be even further increased by the method known per se of deflecting the electrons before they have obtained their final velocity. As shown in Fig. 5, this can be effected in a particularly simple way, by omitting the second anode 16 in Fig. 4 and using the deflector systems themselves as second anode. The final lens can be obtained by joining a further ring to the system or, as shown in Fig. 5, by using the conducting coating of the tube itself as final anode. In this figure 19 is the cathode, 20 the grid, 21 the first anode, 22 the first deflecting system, 23 the second deflecting system, and 24 the conducting coating on the tube envelope. It is of course understood that the electron gun and the lenses as shown in this and the following examples are chosen also by way of illustration and can be replaced by any other known guns or lenses.

Fig. 6 is a diagram, by means of which the resulting deflecting sensitivity can be obtained. This diagram shows the cardinal points of the electron lens corresponding to the actual dimensions of Fig. 5, in the case where the mean potential of the deflecting system is $\frac{1}{4}$ of the final voltage, i. e., if the total driving voltage is 4000 volts and the mean potential of the deflecting plates is 1000 volts. F_1 is the first, F_2 the second focus of the electron lens so formed, H_1 and H_2 are its

two principal planes. By the construction as shown, we can, according to the rules of geometrical optics as well known in connection with thick lenses, obtain the resulting deflection under the approximate assumption, that deflection and concentration are superposed, but do not interfere with each other. We see that the initial deflected beam I leaves the system as the ray II, coming from another pivoting point, under an angle which is only about 58% of the original angle. As a result, the deflecting sensitivity of the system is reduced below the value which would obtain if the electrostatic lens effect were not present.

This can be avoided according to the invention, by passing the deflected beam through the "first nodal point" of the lens. As is shown in the optical theory of thick lenses, every lens has two "nodal points" of the following properties: A ray passing from the object space through the first nodal point "N₁" after having passed through the lens will appear coming from the second nodal point "N₂" in a direction parallel to the original ray. These nodal points can be constructed as shown in Fig. 6. The distance of N₁ from F₂ is equal to f₁, the first focal length, and the distance of N₂ from F₁ is equal to the second focal length f₂. It is seen that in Fig. 5 the nodal point N₁ is at far too great a distance from the pivot point P.

Far higher deflecting sensitivities can be obtained according to the invention by the design as shown in Figs. 7 and 8. Here 25 and 26 are the two deflecting systems. The second is fitted with a conical part 27, and the pivot point P of the rays lies well outside the opening. By the conical shape, however, considerably higher sensitivities are produced; the sensitivity of the design shown in Fig. 7 is for the same deflecting angle very nearly the same as of the design in Fig. 1. Moreover, deflecting fields and focusing fields are more effectively separated. This is even better achieved in the design shown in Fig. 9, in which the deflecting system is covered from the screen side by a truncated cone 28. By giving this cone suitable potentials, somewhat negative against the mean potential of the deflecting system, the penetration of the outer field can be reduced to a great extent. The potential of 28 must not be made too negative, as in this case a lens is formed within the entrance. By this design it is possible to make the deflected beam pass exactly through the first nodal point of the lens.

According to a further feature of the invention, the new deflector system can be operated with suitable combinations of lenses in such a way as to eliminate the "astigmatism" which up to now has been a major disturbing factor in cathode-ray tubes, especially in tubes for television purposes.

Fig. 10 explains the phenomenon of deflection astigmatism. 29 and 30 are the two plates of a deflecting condenser. a and b are two electron trajectories, which are parallel if no deflecting field is acting. If, however, a field is produced, the deflected rays will cross over, as the ray a' nearer the negative plate 29 will suffer stronger deflection than the ray b'. This has two causes: Firstly, the deflected ray b' travels a shorter distance in the deflecting field than the deflected ray a' and secondly, as it is constantly at a higher potential, it is "stiffer" than a'. In magnetic deflecting fields the astigmatism is generally much smaller, as there the second factor rules out. Mathematically the astigmatism in an

electrostatic deflecting field can be expressed by the following relation:

$$\Delta\alpha = \frac{1}{2} \delta \frac{1}{\psi} 2 \left[\frac{\psi \delta^2 \psi}{\delta N^2} - \frac{3}{2} \left(\frac{\delta \psi}{\delta N^2} \right)^2 \right] \Delta N^2 ds \quad (1)$$

In this formula $\Delta\alpha$ is the difference between the angles by which two rays have been deflected, which have passed through a deflecting field, at a distance ΔN from each other; the distance varying in general along the path s . ψ is the potential, measured against the cathode. $\delta\psi/\delta N$ and $\delta^2\psi/\delta N^2$ are the first and the second partial derivatives with respect to the direction n , perpendicular to the trajectory. If—as in most cases— $\Delta\alpha$ is small compared with α , we can calculate this integral with sufficient accuracy assuming that ΔN has varied in the same way along the path s as if no deflection had taken place. In the case shown in Fig. 10 we could e. g. assume $\Delta N = \Delta N_1 = \text{constant}$. We can then carry out the integration if we only know $\psi\delta\psi/\delta N$ and $\delta^2\psi/\delta N^2$ i. e., the potential, the gradient normal to the path, and the gradient of the gradient normal to the path, for one deflected trajectory. In first approximation we can even substitute the values for the undeflected trajectories.

In the case of electrons of the volt-energy E in a homogeneous deflecting field with the constant gradient F , in which the first term in the integral vanishes, this becomes simply

$$\Delta\alpha = -\frac{3}{4} \left(\frac{F}{E} \right)^2 \delta \Delta n dx \quad (2)$$

In view of the small difference between the arc length a and the ordinate parallel to the system axis x I have substituted the latter. We see from this how a homogeneous deflecting field produces astigmatism. The non-homogeneous fringing field of the deflecting plates, which is widely believed to be responsible for it, is in reality beneficial, but its effect is insufficient to compensate it.

According to the invention, I eliminate astigmatism by providing inside the deflecting system a crossing point of the electron rays, i. e., an image of the cathode or of the "cross-over." The above expression (2) then becomes equal to zero, as Δn assumes now positive and negative values.

It can be shown, however, that this method is of no avail in the case of ordinary deflecting systems, but is applicable only to systems according to the present invention, in which deflections are effected in opposite directions. Fig. 11 shows a parallel condenser system, in which an image is produced at the center C . According to equation 2 this system is anastigmatic. We can not utilize it, however, for the following reason: If we want to obtain eventually an image of C on the screen, a lens must be placed behind the deflecting system. As, however, the screen is at a large distance, this means that C must nearly coincide with the first focal point of the lens. As now the pivot point in this deflecting system is also C , this means that the deflection will be nearly completely destroyed by the lens.

This could be assisted by using wedge-shaped or curved deflecting plates. It turns out, however, that the anastigmatic center, i. e., the point in which the rays must cross in order to make the astigmatism zero, will always follow the pivot point at a close distance.

This is, however, quite different in the systems according to the invention, as shown in Fig. 12. Here 31 is the cathode, 32 the grid, 33 the first anode and 34 the second anode. 35 and 36 are

the two deflecting systems, consisting of split cylinders. The anastigmatic center C is in this case again near the center of the whole deflecting system, whereas the pivot point P is at its end, inside the final lens, which is formed between 36 and the final anode 37. It is therefore possible to focus C on the screen without destroying the deflections. The intermediate image C is produced in this example simply by the lens formed between 34 and 35, if the mean potential 10 of 35 is different from the potential of 34. It can be higher or lower; in any case the lens will be a concentrating lens.

The diagram in Fig. 13 shows that the deflection is not destroyed but even increased by this arrangement. This diagram corresponds to the case when the voltage of 37 is seven times the mean potential of the deflecting systems. This potential ratio is necessary for focusing "C" on 15 the screen at a distance of about 30 cms. The construction shows that the deflection angle is reduced to about 52%. This means that the sensitivity is still $7 \times 0.52^2 = 1.9$ times greater than obtainable with a parallel condenser system and 20 the astigmatism is eliminated.

The most advantageous design is, however, the one shown in Fig. 14, which shows a combination of the same electron gun system as in Fig. 12 with the new deflection system as shown in Fig. 9. 25 With this system it is possible to fulfill both conditions which according to the invention make the deflection sensitivity large and the astigmatism zero, namely: The focal point of the final lens nearly coinciding with the anastigmatic center of the deflecting system, and the pivot point of the deflecting system nearly coinciding with the first nodal point of the lens.

With this system it is possible to obtain large deflections without astigmatism, and therefore it is possible to make the cathode-ray tube short 40 and the aperture large. This leads to a television tube construction as shown in Fig. 15 which at equal screen size has a length only of $\frac{1}{2}$ — $\frac{1}{3}$ of the tubes used at present. Apart from the obvious advantage following from the short length, 45 this oscilloscope allows obtaining much smaller spots and much higher brilliance, because both the short length and the large lens aperture are helping to reduce the spot size. Because of the high deflecting sensitivity it requires also only 50 small scanning voltages, and by this helps to reduce the space occupied by the scanning devices in television sets.

In Fig. 16, the cross-connection system referred to in connection with Figs. 1 to 4 is 55 shown in detail. In the arrangement illustrated, electrode 5 is connected to electrode 10 by means of a conductor 40, electrode 6 to electrode 9 by means of a conductor 41, electrode 7 to electrode 12 by means of a conductor 42, and electrode 8 60 to electrode 11 by means of a conductor 43.

In order to energize the deflecting system, a common source 45 of alternating scanning potential is connected across the conductors 40 and 41. In view of the mode of connection indicated 65 it is apparent that the potential applied to the electrode pair 5, 6, is identical in periodicity but opposite in direction of deflecting action to that applied to the electrode pair 9, 10. Consequently, these pairs produce opposite oscillatory 70 deflections of the electron beam traversing them. Similar functioning of the electrode pairs 7, 8 and 11, 12 may be obtained by applying to them a second scanning potential from an appropriate source (not shown). 75

In this application only the outlines of the invention have been described and a few examples given. Other applications of the new principles involved—e. g. for television tubes with magnetic focusing and scanning, separately or together—will be obvious to those skilled in the art.

What I claim as new and desire to secure by Letters Patent in the United States is:

1. In combination, an electron gun for projecting an electron beam along a given axis, a screen to be scanned by the beam and a deflecting system effective to cause the beam to scan the screen, the said system including a first electrode structure operative to produce initial oscillatory deflection of the beam and a second electrode structure arranged sequentially to the first for producing additional oscillatory deflection of the beam in a direction opposite to the said initial deflection, the resulting pivoting point of the beam being adjacent the end of the said second electrode structure which is nearest to the screen, and an apertured electrode positioned between the said second electrode structure and the screen and forming therewith an electron-optical lens, the said second electrode structure being tapered at the screen end and the apertured electrode being shaped to conform to the said taper, whereby the nodal point of the said electron lens is caused to coincide at least approximately with the said pivoting point of the electron beam.
2. In combination an electron gun for projecting an electron beam along a given axis, a screen to be scanned by the beam and a deflecting system effective to cause the beam to scan the screen, the said system including a first electrode structure operating to produce initial oscillatory deflection of the beam and a second electrode structure arranged sequentially to the first for producing additional oscillatory deflection of the beam in a direction opposite to the said initial deflection, the beam being thus given an effective pivoting point relatively near to the screen end of the said second electrode structure, means including an electron-optical lens adjacent the gun end of the electrode structure for producing a cross-over point within the said second deflecting electrode structure at a point different from the said pivotal point and a second electron-optical lens adjacent the screen end of the deflecting structure, the said lens having its focal point substantially coincident with the said cross-over point.
3. A cathode ray tube comprising means including a cathode for producing a beam of electrons, a screen to be scanned by the said beam, beam deflecting structures arranged at two spaced positions along the axis of the tube, said structures including a pair of oppositely disposed electrodes at each position, each of the electrodes at one position being connected respectively to its oppositely disposed electrode at the other position whereby the beam is deflected in opposite directions in passing successively through said structures, means including an electron-optical lens adjacent the cathode end of the first deflecting structure for producing a cross-over point within the said second deflecting structure and a second electron-optical lens adjacent the screen end of the second deflecting structure, the said second lens having its focal point substantially coincident with the said cross-over point whereby anastigmatic deflection of the beam is obtained.

4. A cathode ray tube comprising means including a cathode for producing a beam of electrons, a screen to be scanned by the beam, two beam deflecting structures arranged sequentially along the axis of the tube, each structure including two pair of mutually perpendicular electrodes arranged in substantially closed configuration and each of the electrodes of the first structure being connected to an oppositely disposed electrode of the second structure, whereby the beam is deflected about a pivoting point relatively close to the screen end of the second structure, means including an electron-optical lens adjacent the cathode end of the first beam deflecting structure for producing a cross-over point within the second deflecting structure and means including a tapered portion at the screen end of the second deflecting structure and a conical electrode conforming with the said tapered portion for providing an electron-optical lens having its focal point substantially coincident with the said cross-over point, whereby the deflection of the beam is rendered anastigmatic.

5. A cathode ray tube comprising means for producing a cathode ray beam, a screen to be scanned by the beam and a deflecting system effective to cause the beam to scan the screen, the said system including a first electrode structure operative to produce initial oscillatory deflection of the beam and a second electrode structure arranged sequentially to the first for producing additional oscillatory deflection of the beam in a direction opposite to the said initial deflection, the resulting pivoting point of the beam being adjacent the end of the said second electrode structure which is nearer to the screen, and an apertured electrode arranged in partially telescoping relation with the said end of the second electrode structure, the two last-named parts being of such configuration as conjointly to provide an electron lens having a nodal point approximately coincident with the said pivoting point of the beam.

6. In combination, means for projecting an electron beam along a given axis, a fluorescent screen to be scanned by the beam, and deflecting means including two mutually perpendicular electrode systems operable to cause the beam to scan the entire surface of the screen in successive increments, each of said electrode systems including a first pair of electrodes effective when subjected to a potential difference to exert a deflecting force on the beam in a given plane parallel to the beam axis, a second pair of electrodes arranged sequentially to the first and in substantial alignment therewith, said second set of electrodes being dimensioned to act on the beam for a substantially greater portion of its path length than the first pair and effective when subjected to a potential difference to exert a deflecting force in the same plane as said first pair, and means for applying to said first pair an alternating potential difference of constant amplitude and desired scanning periodicity and to said second pair an alternating potential of similar amplitude and periodicity but of reversed direction of action.

7. In combination, means for projecting an electron beam along a given axis, a fluorescent screen to be scanned by the beam, and deflecting means including two mutually perpendicular electrode systems effective to cause the beam to scan the entire surface of the screen in successive increments, each of said systems including a first pair of oppositely disposed electrodes op- 71

erating to produce initial deflection of the beam in a given plane paralleling the axis of the beam, a second pair of oppositely disposed electrodes arranged sequentially to the first and in substantial alignment therewith for producing additional deflection of the beam in the said given plane, the electrodes of the said first pair being cross-connected to the electrodes of the said sec-

ond pair and there being a common source of alternating potential of constant amplitude for energizing both pairs of electrodes whereby the respective electrode pairs are effective to produce opposite oscillatory deflections of the electron beam.
